TWO-CYCLE GAS ENGINE

Friedrich Hagenmüller and Ludwig Prechtel, Nuremberg, Germany, assignors to Maschinenfabrik Augsburg-Nürnberg A. G., Nuremberg, Germany, a corporation of Germany

Application June 24, 1932, Serial No. 619,010
In Germany December 28, 1931

3 Claims. (Cl. 123—69)

Our invention relates to a two-cycle gas engine capable of attaining high outputs at high speeds.

High power gas engines—i. e. gas engines of several thousand H. P.—heretofore known run slowly, are very large and heavy and are accordingly very expensive to purchase and to erect. It is well known that engines of higher speeds have smaller dimensions, and attempts have, therefore, been made to construct such engines. 10 Such attempts however, have only led to designs which have proved impracticable.

One of the chief obstacles has been that the organs of distribution for the quantity of gas and air to be dealt with were of such a size and weight that at higher speeds the forces of acceleration could no longer be overcome. These difficulties are overcome by the present invention providing for not only the exhaust but also all air admission (including scavenging air) being 15 governed by ports and working piston only. Thus, the problem of the forces of acceleration for air valves is disposed of. As far as the gas is concerned, the difficulty of keeping the gas valve, through which at high outputs a considerable quantity of gas has to flow, within admissible limits as regards size and weight, is overcome by the admission of the gas as quickly as possible after closure of the exhaust ports, so that, on the one hand, the time available for forcing in the 20 gas is ample to enable the use of a small gas valve, and, on the other hand, the gas pressure remains comparatively low so that a light compressor is sufficient. Furthermore, sufficient time remains for a thorough mixing of the gas and air in the 25 working cylinder before ignition.

It is also important that the gas valve be provided with a positive valve gear. Only with such a device can the necessary precision be obtained as regards the moment of the opening and closing 30 of the gas valve which as will be seen from the foregoing is important for the operation of the engine, and only with such a device can the engine run at high speeds. Thus, automatic inlet valves for the gas, or valves whose opening 35 is dependent upon the pressure in the cylinder and which have no external positively driven members are of no use.

On the annexed drawings, on which are shown, 40 by way of illustration, embodiments of an engine designed in accordance with the present invention,

Fig. 1 shows a double acting two-cycle gas engine, the essential parts of which are shown in 45 section, the other parts being shown in elevation.

Figs. 2 and 3 show a two-stroke gas engine, certain parts being omitted.

According to Fig. 1, the cylinder 1 has in the center four superposed ports 2, 3, 4 and 5. The ports 3 and 4 are provided for the admission of the scavenging air, which is supplied to said ports by an electrically driven blower 6 through the pipe 7 in which a collector 8 is fitted.

Ports 2 and 5 are exhaust ports leading to the open through pipes 9 and 10 in which collector 10 vessels 11 and 12 are fitted.

Each cylinder end has a gas inlet valve (shown at 13 and 14 respectively). The piston 15 inside the cylinder drives the crankshaft 19 in the direction of the arrow 20 through piston rod 16 connecting rod 17 and crank 18. The direction of turning is shown by arrow 20.

The lower end of the piston 15 controls the ports 2 and 3, while the upper end controls the ports 4 and 5. The ports 2 and 3, and 4 and 5 respectively are opened when the controlling end of the piston moves to the center of the cylinder, and are closed when the controlling end of the piston moves from the center of the cylinder upwards or downwards, as the case may be. More 25 exact details are given below.

The gas valves 13 and 14 are operated as follows:—

A wheel 21 mounted on the crankshaft 19 drives the equal-sized wheel 23 by means of the transmission 22 so that the cam disc 24 secured to wheel 23 rotates at exactly the same speed as the shaft 19. Contacting with the edge of this cam disc at two diametrically opposite points are 30 rollers 25 and 26 each of which is carried by a lever system. The lever system for the upper gas valve 13 consists of the levers 27 and 28 and rod 29, while that for the lower gas valve 14 consists of bell-crank lever 31. The ends of levers 28 and 31 bears against spring-actuated stems 30 and 32 of the gas valves 13 and 14.

As the cam disc 24 rotates in the direction of the arrow, cam 33 first lifts the upper roller 26 thus opening the gas valve 13 for a brief time. 45 After a revolution of 180° the cam reaches roller 25 and opens gas valve 14 which immediately closes again after the cam has passed.

The compressor 34 draws gas through the pipe 35 and forces it through piping 36 and the two branches 37 and 38 to the valves 13 and 14 through which at the moment they open the gas enters the cylinder. In the piping 36 is a collector 39 for compensating any sudden fluctua- 50 55

tions in the flow of gas through piping 36, 37 and 38.

Now, the operation of the engine will be described as regards the upper end of the cylinder.

- 5 When the piston occupies its lowermost position scavenging air enters the cylinder 1 through port 4 driving the burned gas out of the cylinder through exhaust port 5.

Now, when the piston moves upwards, its upper 10 end first closes the scavenging air port 4, and then the exhaust port 5. As shown in Fig. 1 of the drawings, which also shows the corresponding position of the connecting rod 17, the crank 18, and the cam disc 24. The cam 33 carried by the 15 disc 24 acting through the roller 26 and the lever system 27, 29, 28, 30, on the gas valve 13 the latter commences to open, and gas enters the cylinder. The gas admission is completed, when the upper 20 end of the piston has about reached the position shown by the upper dash-and-dot line. Then follows the compression of the charge, and, shortly before the upper dead point of the piston, ignition and explosion, resulting in the descent of the piston. As soon as the upper end of the piston 25 reaches the dotted line position 42 the burned gas flows through port 5 into the exhaust pipe 10. Then, at the dash line position 41, scavenging port 4 is opened, scavenging air enters the cylinder and drives out the rest of the gas. Then the cycle 30 is repeated.

The design just described differs from all previous designs of gas engines, apart from other characteristics, particularly in the admission of the gas immediately the cylinder is entirely 35 closed. With previous designs the gas admission has taken place either while the exhaust was still open so that gas could escape with the exhaust, or so late that the compression period was almost at an end and high pressure already existed in 40 the cylinder so that the gas also had to be put under high pressure before admission was possible.

As to the lower end of the cylinder the operation 45 is the same as the one just described and it is therefore not necessary to describe it separately.

The two-stroke gas engine according to Fig. 2 is also designed in accordance with the present 50 invention but in addition has a device for admitting air, after the closing of the exhaust ports, into the upper half of the cylinder when the piston moves upwards and into the lower half of the cylinder when the piston moves downwards. 55 This device consists of a port 44 for the upper and a port 45 for the lower half of the cylinder. Each port is controlled by a rotary slide valve 46 for port 44 and 47 for port 45. Instead of rotary slide valves ordinary valves can of course 60 be used. These rotary slide valves are driven by the crankshaft 19 in the usual way (not shown) so that at the proper time air from the piping 48 enters the cylinder. This can take place either simultaneously with the admission of gas 65 through either gas valve 13 or 14, or before, or, if the ports are provided nearer the ends of the cylinder, afterwards. The purpose of this introduction of compressed air is well known and therefore, does not require explaining here.

70 The two diagrams show single-cylinder engines.

The same design can, of course, be applied to multi-cylinder engines, several cylinders being arranged side by side and transmitting their power on to the same crankshaft in the usual way. In this case, of course, only one scavenging air blower and one gas compressor are required for all the cylinders.

5 The principle of this invention can be applied without alteration to a single acting engine, as well as to the double acting engine illustrated. 10 It would not appear to be necessary, however, to make a separate description of this.

Engines constructed in accordance with this invention may, without deviating from the principle of the invention, also include devices or 15 systems already known in engine construction and which also in this case can be of advantage. For instance, as shown in Figure 3, rotary slide valves 49 and 50 can be fitted into the exhaust pipings 9 and 10, close to the ports 2 and 5. These 20 valves close the exhaust ports as soon as the piston has closed the respective scavenging port, so that gas can be admitted without waiting for the piston to close the exhaust ports.

25

We claim:

1. A high speed high power two cycle internal combustion engine comprising a cylinder having an intake port, an exhaust port and a port for the supply of scavenging air, a piston reciprocal within said cylinder, the exhaust port and the 30 scavenging air supply port being disposed to be successively uncovered by the outer end portion of the piston during inward movement of the piston and immediately prior to the piston reaching its limit of inward movement within the cylinder, the scavenging air supply port being disposed entirely inwardly of the exhaust port, means for supplying scavenging air under constant high pressure through said scavenging air port and in greater volume than the piston displacement during the time that said scavenging air port is uncovered, the intake port being located in the cylinder head, a normally closed 35 valve controlling said intake port, means for opening said valve immediately after the piston 40 during its outward movement has closed the exhaust and scavenging air ports, means for forcing explosive gas into the cylinder through said intake port during outward movement of the piston and prior to the outward movement of the 45 piston resulting in an appreciable pressure being generated within the cylinder, and means whereby said intake valve is closed prior to the piston reaching its limit of outward movement. 50

2. An internal combustion engine as set forth in claim 1 including valve means operable to close the exhaust port when during outward movement of the piston and prior to closing of the exhaust port by the piston the same has closed the scavenging air port. 55

3. An internal combustion engine as set forth in claim 1 including means for the introduction of air into the cylinder between the cylinder head and the exhaust port during outward movement of the piston and following closing of the scavenging air port and the exhaust port by the 60 piston. 65
